UNITED STATES PATENT OFFICE.

GERRET HOLTLAND, OF ENSCHEDE, NETHERLANDS.

COUNTING MONEY, TOKENS, OR THE LIKE, OF THE SAME SIZE.

Application filed March 20, 1921. Serial No. 456,872.

To all whom it may concern:

Be it known that I, GERRIT HOLTLAND, engineer, a citizen of the Kingdom of the Netherlands, residing at Enschede, Netherlands, have invented certain new and useful Improvements in Counting Money, Tokens, or the like, of the Same Size, (for which application for patent was filed in the Netherlands under date of June 11, 1919, No. 12,188, Patent No. 6,295), of which the following is a specification.

My invention relates to a device for counting coins or tokens of the same size, by means of a number of gradually arranged supports and has for its object a device, as simple as possible and adapted not only to count exactly in a very short time a large sum of money without mistake, but providing also during the counting for inspection of the money, the latter being specially required to enable spurious and worn coins to be detected.

In the accompanying drawings:—

Figure 1 is a plan view of the device for use by hand, with adjustable magazines.

Figure 2 is a sectional view through A—B of the magazine of Fig. 1.

Figure 3 is a sectional view seen from the right of Figure 1, at C—D.

Figure 4 is a sectional view seen from the right of Figure 1, at E—F. Fig. 4^a is a detail view of the elements 6 and 7.

Figure 5 is a device for gradually supplying coins to the stationary devices.

Figure 6 is a diagrammatical sketch of a device for adjusting the supports in the breadth.

Figure 7 is a sectional view through G—H in Figure 6.

Figure 8 is a diagrammatical view of a device for moving the slides in order to adjust the magazines in breadth and length.

Figure 9 is a section through K—L in Figure 8 of a slide for controlling the length of the magazines applied to devices for counting coins of different size.

Figure 10 is a side view of a flap or valve for closing the outlet ends of the magazines.

Figure 11 is a longitudinal section of the funnel-shaped mouth of the collecting gutter.

Figure 12 is a section of an adjustable mouth-piece.

Similar references throughout the several figures indicate the same parts.

By 1 are indicated the magazines or con-

ductors of the coins (Fig. 2) with vertical projecting rims 2, against which the coins on sliding along the inclined bottom will strike. The conducting gutter in the magazines possesses a breadth corresponding with the diameter of the coins to be counted, whilst the rims 2 are less high than the thickness of the coins.

The arrow (Fig. 1), indicates the supply direction. To fill the magazines, the device as illustrated in Fig. 1, is inclined so that the coins slide from the part 9 through the supply gutter 4 till all magazines 1 are filled up; the movable side wall 3 is then lifted and by giving the device a suitable inclination the coins slide along the rims 2 into the collecting gutter. The superfluous coins are collected in the part 10 and returned by the gutter 11 to the collecting part 9.

For moving the coins, the device is kept in such a position, that the inlet is situated higher than the outlet and the apparatus is somewhat inclined in a lateral direction.

As the magazines are at an angle with the supply direction of the coins, the same will not only slide beyond the already arrived coins of one of the magazines into another, but also fill the same magazine as much as possible in the direction of the outlet.

To enable the superfluous coins to descend also to the inlet sides of the magazines beyond the coins already arrived at their places, vertical screens 6 and steps 7 are provided.

The screens 6 are arranged parallel to the axis of the magazines and situated between two adjacent steps 4 and the projecting rim of the following magazine. Every magazine is provided with such a screen. The steps 7 are high as the projecting rim 2 of the preceding magazine and reach as far into the conducting space of the magazine as required to guide the coins beyond the already arrived coins, to the not yet occupied places, without hindering the coins.

Between the screens and the side wall of the receptacle, small recesses are formed, the bottoms of which are situated at the same plane as the step surface.

The device for hand use as illustrated in Fig. 1, is provided with magazines 1 and rims 2, an inlet port 4, a collecting gutter 8 with mouth 5, a collecting receptacle 9, a space 10 for the superfluous coins and a re-

turning gutter 11 for removing the latter to the inlet 4.

First the coins are moved to the inlet part 4 by inclining the device to the left. Then, 5 by inclining to the right, the coins move beyond the magazines to the part 10, thereby filling up all the magazines 1 so that for instance the coins are placed in five rows each of 10 coins. By opening the flap 3 at 10 the end of the magazines and by inclining the device to that side, the coins may be collected in the collecting gutter 8 and received by means of the mouth 5 in paper boxes.

The flap 3 for the outlet ends of the 15 magazines 1 into the collecting gutter 8 consists in its most simple form of a shaft 30 provided with a handle 37, turnable in the receptacle (Fig. 3), to which shaft rectangularly bent hooks 12 are attached, 20 which in normal position reach exactly to the middle of the outlet mouths. The ends of these hooks 12 gradually increase in length so as to open the mouths one after the other, when the shaft 30 is rotated by 25 means of the handle 37. By this manipulation, only coins from one of the magazines may reach the gutter 8. It will be understood that the mouths of the magazines open successively (from an inspection of 30 Fig. 10). In this modification the simple curved hooks 12 are replaced by a curved bent plate with graduated edge. By turning the shaft 30 all the hooks 12 or the parts of 3 have the same angular movement and 35 speed, but as the first hook is shorter than the second one and all mouths are situated in the same horizontal plane, and because in the closed position the longer hook will extend farther under the edge of the mouth 40 than the shorter one. It will require a greater length of time before the end of this hook has entirely passed the mouth of its magazine and opened the same.

For big devices for counting large quantities of coins the use of a hand-operated device is too troublesome and takes too much time, so that a stationary device must be used. The removing back of the superfluous coins can take place automatically or not; it is important only that the supply shall take place as gradually as possible, because if a suddenly greater stream of coins slides over the magazines, most of them will not enter into the same.

55 For this purpose a device, as illustrated in Fig. 5, is applicable, consisting of a receptacle or cylinder 13 with an inclined bottom 14, movable up and down by hand or foot, which bottom supports the coins. 60 The coins will run down as soon as the pile has reached a determined height above the opening 15 with the inclined flange 16.

A superfluous supply is prevented by a 65 triangular pin or stud, arranged above across the cylinder which prevents a too

high piling of the coins, as these will strike against the stud when the pile reaches a predetermined level. The coins collected on the bottom 14 will form a pile and this pile will strike against the triangular pin when 70 the bottom 14 is moved upwardly. The pin will thus not prevent the coins from piling up, but determines a point above which the pile will not extend, in order to provide a sufficient supply of coins in the counting 75 apparatus. If the hopper is filled above the triangular pin more coins will flow into the counting apparatus than can be counted simultaneously and therefore the triangular pin is arranged at such a height over the 80 under edge of the opening 15 that the coins only will flow in the desired number to fill gradually the supports 1 of the apparatus when the coin pile reaches this pin.

The bar 17, attached to the bottom is 85 provided at the other end with a piston 18 with a small perforation 19 acting as a buffer, nearly closing the chamber 20, to prevent shocks.

With such a supply device it is possible 90 to build the device in a compact form though it will be adapted to count large quantities, as the coins are stored below the inclined delivery flange 10. This cylinder also supports the inclined bottom 14. 95

In order to count with the same device coins of different sizes, it is necessary that the magazines be adjustable in length and breadth. Figs. 6 and 7 illustrate the manner of adjusting the breadth by means of 100 link devices 21 and 22. Each magazine 1 is therefore carried by a strap 31, supported by a bolt 32, and at the same time serving as a pivot for the link, and are guided by two rods 26 and 33, between which rods the 105 link device 34 (Fig. 7) is situated. The magazine at the inlet side is fixed, while the other magazines are simultaneously movable along said rods, so that an exact adjustment may be easily obtained. In order 110 to conduct the coins better, a stud 35 is provided at the highest situated part of the magazines next to the steps, which stud engages in a similar slot 36 of the next magazine.

115 Figs. 8 and 9 illustrate a device to adjust the magazines in the length, corresponding to the sizes of the coins to be counted. 23 are here the controlling devices of the magazines consisting of flat cast arms 23 controlled by a spring 23^a and separated from each other by coiled springs 38 attached on the axle 24. This axle 24 is rotatable in two blocks 39 and 40, slidably mounted on the rods 25 of a frame. One rod 25 is fixed, the other is slidably attached to the rods 26.

Between the last flat arm 23 and the block 39 is also a coiled spring, whilst the arm at the other end is kept in place by a nut 41. By turning the nut 41, all the 120

coiled springs are equally compressed or expanded, so that the flat arms 23 still remain equally spaced.

To expand the magazines, the movable rod 5 and the nut 41 and with them the flat arms 23 are adjusted corresponding to the breadth of the magazines.

By moving the axle 24 along the rods 25, it is possible to limit the room to be filled 10 by the coins to correspond, for instance, with ten coins of a determined diameter.

In order to be able to lift the flat arms 23 one after the other (Fig. 9) in order to empty the magazines one after the other, 15 a lever is fixed to the rod 24, whilst the different arms 23 with gradually decreasing space are attached to the rod 24, and the arms 23 are in this way gripped and lifted up one after the other.

20 In order that the coins or tokens reach the paper boxes in the correct position, in which boxes the coins are finally received and packed up, a funnel is placed in the outlet mouth, as shown in section in Fig. 11, 25 the mouth diameter of which is a little larger than that of the coin and a little smaller than that of the paper box.

In devices for coins of different sizes the funnel outlet part is adjustable, as shown 30 in Fig. 12.

What I claim as my invention is:

1. In a device for counting coins or tokens of the same size, a plurality of stepped magazines, the breadth of which is equal 35 with the diameter of the coins, a receptacle supplying the coins to be counted, the bottom of which is formed by said stepped magazines, a vertical rim less high than the thickness of the coins provided on the entire length of said magazines and a movable closure at the ends of said magazines.

2. In a device for counting coins or tokens of the same size, a plurality of stepped magazines, the breadth of which is equal

to the diameter of the coins, a receptacle 45 supplying the coins to be counted, its bottom being formed by said magazines, a vertical rim mounted on the entire length of the same, and a movable closure at the ends of said magazines, the latter being disposed at an angle with the supply-direction of the coins.

3. In a device for counting coins or tokens of the same size as set forth in claim 2, steps 50 for filling the magazines disposed at the end opposite the outlet of the same, the upper surfaces of said steps being in the same plane as the rim of the preceding magazine, recesses formed by the wall of said receptacle and by screens parallel with the support 55 axis, said screens being arranged between the edge of the step and the projecting rim.

4. A device for counting coins or tokens of the same size as set forth in claim 2, further characterized in this that said magazines abut at the outlet end upon collecting gutters, the mouths of which may be closed by valves, which may be moved so as to successively open the mouths.

5. In a device for counting coins or tokens of the same size as set forth in claim 2, link devices for adjusting the breadth of the magazines and connected therewith in such a way that the magazines may slide one on the other; means for adjusting the length 75 of said magazines, spaced by coiled springs and mounted on a rotatable shaft, said means being adjustable both in the direction of the magazine-axis and in the supply-direction of the coins.

In testimony whereof, I have signed my names to this specification in the presence of two subscribing witnesses.

GERRIT HOLTLAND.
